JUSTUS DOERING, OF PHILADELPHIA, PENNSYLVANIA, ASSIGNOR TO
HIMSELF, A. F. SHELLY, AND CHARLES DIXEY, OF SAME PLACE.

Letters Patent No. 72,986, dated January 7, 1868; antedated December 26, 1867.

IMPROVEMENT IN STOP-COCKS.

The Schedule referred to in these Letters Patent and making part of the same.

TO ALL WHOM IT MAY CONCERN:

Be it known that I, JUSTUS DOERING, of Philadelphia, Pennsylvania, have invented an Improvement in Stop-Cocks; and I do hereby declare the following to be a full, clear, and exact description of the same, reference being had to the accompanying drawing, and to the letters of reference marked thereon.

My invention consists of certain improvements, fully described hereafter, in stop-cocks, to be used in connection with hydrants, or whenever the cock has to be placed at a point difficult of access, the improvement being such that the plug can be readily withdrawn from its seat, repaired, and as readily returned.

My invention further consists of a modification, to be used in connection with hydrants and filters.

In order to enable others skilled in the art to make and use my invention, I will now proceed to describe its construction and operation, reference being had to the accompanying drawing, which forms a part of this specification, and in which—

Figure 1 is an outside view of my improved stop-cock,

Figure 2 a sectional view of the same,

Figure 3 a plan view, and

Figure 4 a modification of my invention.

Similar letters refer to similar parts throughout the several views.

Between the discharge-pipes A and A', and in the casing B of a stop-cock, is formed a conical opening, *a*, for the reception of a hollow conical sleeve, C, which is prevented from turning in the same by lugs *b b*, which form a part of the sleeve, and rest between projections *c c*, situated above and on each side of the opening *a*. When the sleeve is thus inserted, its openings, *d d*, are in line with the pipes A and A'. A conical plug, D, is inserted into the sleeve C, and is secured in its seat by a screw and washer, *e*.

In stop-cocks of ordinary construction which are placed beneath the surface of the ground, and operated from above, such, for instance, as those used for hydrants, the plug has its seat in the casing B of the cock, and is secured to the same in such a manner that it cannot be detached until the earth is removed from above. If the plug becomes jammed in its seat, or the cock leaks, the repairing of the same is a matter involving considerable delay and expense. This objection is obviated by the employment of the sleeve C, which, with the plug, can be readily lifted out of the opening *a*, repaired, and returned to its place, or a new plug can be introduced.

The modification of my invention shown in fig. 4 is to be employed where a filter is used in connection with the hydrant. The water flows through the pipe A, through the openings of the sleeve C and plug D, and through the pipe A', which leads to the filter. The pipe E is for the passage of the purified water from the bottom of the filter, and the pipe F for the ordinary hydrant-water from the top of the same, and communication is opened with either of these pipes, as desired, by turning the plug to the right or left.

I claim as my invention, and desire to secure by Letters Patent—

The combination of the case and conical valve of a cock, and a conical stationary sleeve, fitting the case, and in which the valve turns, and which is so constructed and connected to the valve that it may be withdrawn with the latter from the case without the necessity of detaching any nuts or other fastenings, all substantially as described.

In testimony whereof, I have signed my name to this specification in the presence of two subscribing witnesses.

JUSTUS DOERING.

Witnesses:

WM. HALL WAXLER,
CHARLES HOWSON.
